Charles Lehmann

United States Patent Office.

CHARLES LEHMANN, OF HARTFORD, CONNECTICUT.

Letters Patent No. 101,281, dated March 29, 1870.

IMPROVED STIRRER AND EGG-BEATER.

The Schedule referred to in these Letters Patent and making part of the same.

To all whom it may concern.

Be it known that I, CHARLES LEHMANN, of the city and county of Hartford and State of Connecticut, have invented certain new and useful Improvements in Stirrers suitable for Beating Eggs, mixing liquid substances, or for mixing or combining any materials capable of being mixed or combined by such a machine as is hereinafter described and set forth, and to enable others skilled in the art to make and use the same, I will proceed to describe, referring to the drawings, in which the same letters indicate like parts in each of the figures.

The nature of this invention will be understood from the specification and drawings.

Figure 1 is a side elevation showing the vessel in section.

Figure 2 is a top view of the same.

It consists of a cylindrical vessel, *a*, having an axis hub, *b*, in the center of the bottom, *c*; it is also provided with a cross-bracket, *d*, secured in a detachable manner across the center and near the upper edge of the vessel.

e is a perpendicular shaft, the lower end taking its bearing in or upon the hub *b*, the upper end having its bearing in or on the bracket *d*. This shaft is provided with arms, *f*, which radiate in a spiral form from the shaft, and extend nearly to the outside wall of the vessel, *a*. The outer ends of these arms, *f*, in number more or less, are held and steadied in a firm uniform position by a rim, *g*, secured to the outer end of each arm. These arms are made flat, of a paddle-shape, and their faces arranged slightly inclined so that as the shaft, *e*, rotates the substance within the vessel *a* will be agitated and lifted or elevated upward from the bottom.

h are perpendicular breakers secured to the edges of the arms *f*, in numbers more or less as desirable, the object of which is to divide, break, and cause the parts thus broken to mingle or compound together.

A pulley or crank, *i*, is attached to the shaft, *e*, for the purpose of propelling the stirrer. The material of whatever kind is placed in the vessel, *a*, and motion is imparted thereto by means of the pulley or crank, *i*, through the stirrer. The action of the stirrer upon the material placed within the vessel is to thoroughly stir up and commingle the particles together, or in other words the shape and position of the breakers, and the position of the paddle-shape arms agitate the mass, and change it or displace it from its position near the outside of the vessel toward the center of the vessel, and from the bottom upward, thus continually stirring, changing, and compounding the mass until the whole is formed into the desired condition or compound.

I believe I have thus shown the nature, construction, and advantage of this invention, so as to enable others skilled in the art to make and use the same therefrom.

What I claim, and desire to secure by Letters Patent, is—

The spirally-formed stirrer, composed of the shaft *e*, arms *f*, rim *g*, and beaters *h*, in combination with the vessel *a*, substantially as and for the purpose set forth.

CHARLES LEHMANN. [L. S.]
